LOCK

Filed July 16 1925

Inventor

MORRIS SHEINMAN

By His Attorney

Menachem Rock

UNITED STATES PATENT OFFICE.

MORRIS SHEINMAN, OF NEW YORK, N. Y.

LOCK.

Application filed July 16, 1925. Serial No. 43,922.

This invention relates to locks and in particular to one which can be used in combination with a latch to serve as an anti-jimmy agent or can be used separately to prevent 5 jimmying of the door or otherwise forcing it open from the outside.

A particular object of the invention is to provide an auxiliary lock which comprises a separate locking bar which extends across 10 the meeting point of the door and frame and engages a keeper plate in such manner as to prevent the opening of the door should the same be forced away from the frame.

A further object is to provide a lock of 15 this character which will also lock the outer latch when the inner lock is placed in position and the tumbler barrel of the inner lock revolved after locking said inner lock.

Referring to the drawing wherein I have 20 shown a preferred embodiment of my invention:

Figure 1 is a view of the inside of a door showing my improved lock in locked position,

25 Figure 2 is a partial view of the lock as seen in Figure 1, the locking lever being shown in unlocked position to release the bar,

30 Figure 3 is a section taken on line 3—3 of Figure 1 and shows the outer latch lock and its connections through the door with the inner bolt lock,

35 Figure 4 is a front view of the bar locking member showing the position of the lock plate or member in locking position,

Figure 5 is a section on the line 5—5 of 40 Figure 4, the tumbler barrel being shown in full,

Figure 6 is a view of the reverse side of 45 the locking bar, the reverse side being the one which is normally against the door;

Figure 7 is a section on the line 7—7 of Figure 6, the keeper plate on the frame of the door being shown in outline, and

50 Figure 8 is a section taken on the line 8—8 of Figure 3 showing how the lock is attached to the door.

Referring to the drawing in detail 5 indicates a portion of a door and 6 a portion 55 of a door frame to the former of which is attached in the usual manner the latch 7 which is of any well known make employing the serrated key to operate a tumbler barrel combination, the barrel being shown dotted as at 8 in Figure 3 and having its end slotted in the usual manner to receive the

projecting finger 9 of an auxiliary lock barrel 10 which forms a part of my present improvement. It is to be understood that no particular form of lock is referred to 60 as I may use any suitable key operated combination. For illustration I make use of a lock which is key operated at one side of the door and in turn transmits the revolving motion of the tumbler barrel to 65 another adjacent lock or latch on the opposite side of the door, so that both may be operated from one side of the door.

The auxiliary lock 11 therefore comprises the barrel 10 which is held within a pin 70 housing 12 which fits into a suitable bore 13 in the door 5, the barrel 10 being held in the housing through the medium of a disk 14 secured thereto by screws 15, the disk edge overlying the edge of the housing 75 12, while the opposite end of the barrel extends into a cup-like locking member 16 and has cast integral therewith a lock lever 17, the ends of which are cut on a radius to fit and operate within the overturned 80 edges 18 of the lock bar 19 as shown in Figure 7; when the barrel 10 is revolved by a key which is inserted in the keyhole 20 in the end of the same and adjust the tumblers or pins 21 shown in dotted lines 85 in Figure 3 so that the barrel can be revolved by the key. The disk 14 carries the projecting finger 9, above referred to, so that any movement of the barrel 10 is conveyed to the barrel 8 of the latch. 90

The housing 12 may be cast integral with the cup locking member 16 and has at its inner end the wings 22 through which pass the screws 23 which engage a plate 24 which bears against the opposite side of the door to hold the lock in position, the tightening of the screws serving to compress the wood of the door between the plate 24 and the cup-like locking member 16, as shown in Figure 8. 100

It will be evident therefore, that a revolving movement of the barrel 10 through the medium of an inserted key will revolve the lock lever 17 to engage its ends within the turned over edges 18 of the lock bar 19, and a further revolving movement of the key will operate the lock on the other side of the door. 105

The lock bar 19 it will be noticed has its end enlarged as at 25 to snugly fit within 110 the cup-like locking member 16, the turned over edges of the bar being normally ar-

ranged around the top and bottom and being spaced at their ends substantially the width of the lock lever 17, so that when the lock lever is horizontal the lock bar 19 can be drawn or lifted out of the locking member while its opposite hooked end 26 can then be drawn out of the opening in keeper plate 27.

If desired the auxiliary lock can be used 10 alone, as it will prevent any jimmying of the door or spreading of the frame, and in this case the wings 22 of the barrel housing together with the plate 24 can be dispensed with and as shown in Figure 5, 15 the door can be provided with a well or bore 28 into which fits the barrel housing 29, the cup-like locking member being provided with openings through which screws 30 may pass to hold the locking member in position 20 against the door.

The lock bar 19 is provided with an opening 31 through which passes the end of the barrel 10 when the bar 19 is in position in the locking member 16.

25 It will be evident that the door is securely locked when the lock lever 17 is in vertical position with its ends engaging the end of the lock bar 19 and a further locking movement of the barrel 10 also locks the other latch.

30 It is evident therefore that I have provided a means for locking both sides of a door from one side thereof and also a locking member which prevents separation of the door and frame as is usual when a 35 door is jimmied. Also by providing a stout locking bar it makes it almost impossible to enter unless the proper key is used to release the locking bar.

40 Having described my invention what I claim is:

1. A lock arrangement for doors consisting of a latch lock adapted to be positioned on one side of the door, and a bar lock at the opposite side of the door, said bar lock 45 comprising a receptacle, a lock lever therein, a separable bar adapted at one end to engage said lock lever and at its other end to engage a keeper plate, and means for locking said lock lever, said means being 50 also operable to lock the latch on the opposite side of the door.

2. The combination with a door having an opening therein of a latch lock on one side of said door, a bar receiving and locking receptacle on the opposite side of said door, a locking lever therein, means for operating said locking lever, said means extending into said opening, and an extended portion on said operating means for engaging 55 said latch lock whereby the latter is operated by the locking lever operating means.

3. A lock comprising a cup-like receptacle portion and an extended portion the latter 60 being adapted to fit into an opening in a door, a locking lever in said receptacle, a bar having an enlarged end adapted to fit into said receptacle and be locked therein by the locking lever, and the other end of 65 said bar being bent, and a keeper plate through which said bent end of the bar is passed.

4. A lock arrangement for doors consisting of a latch lock on one side of the 70 door, a bar lock at the opposite side of the door, latch lock operating means on the said bar lock, and a keeper plate and an anti-jimmie agent associated with the keeper plate and the said latch lock operating 75 means.

MORRIS SHEINMAN.
